UNITED STATES PATENT OFFICE.

PETER C. RITCHIE, OF TREMONT, NEW YORK.

SCHOOL-SLATE.

SPECIFICATION forming part of Letters Patent No. 360,327, dated March 29, 1887.

Application filed June 10, 1886. Serial No. 204,747. (No model.)

To all whom it may concern:

Be it known that I, PETER C. RITCHIE, a citizen of the United States, residing at Tremont, in the county of New York, in the State 5 of New York, have invented new and useful Improvements in Slates, of which the following is a specification.

The object of my invention is to provide a slate with a novel frame of a noiseless material, 10 which is at the same time impervious to water or moisture, so that the frame does not become dirty and sticky as with ordinary woolen muffling-strips.

The general construction of my slate-frame 15 is more fully pointed out in the following specification and claim, and illustrated in the accompanying drawings, in which—

Figure 1 represents a face view of a slate provided with a water-proof muffling-strip. 20 Fig. 2 is a transverse section thereof in the plane $\alpha\alpha$, Fig. 1. Fig. 3 is a cross-section of the attaching frame.

Similar letters indicate corresponding parts.

In the drawings, the letter A designates a 25 piece of slate such as is ordinarily employed in the manufacture of slates, B is the muffling-strip, and C is the attaching-frame.

The attaching frame is made of thin sheet metal, which is bent so that it can be passed 30 over the edges of the slate, and it is provided in its length with numerous burrs or projections, c, which project inward toward the slate, and can be formed by depressing the material at selected points. The muffling-strip consists 35 of a long piece of a water-proof material, such as oil-cloth, rubber, and the like, and to secure the same to the edges of the slate its longitudinal edges b b are introduced between the

attaching-frame and the slate, and the attaching-frame is then pressed together upon the slate, whereby the muffling-strip is securely clamped all around its edges. The burrs on the attaching-frame penetrate the material of the muffling-strip and add greatly to the security of the fastening.

Heretofore muffling-strips have been made of flannel or other noiseless material, all of which are more or less liable to absorb moisture—for instance, when the slate is washed with a sponge moistened with water—after 45 which dust or dirt readily adheres to the muffling-strip, and it becomes very unsightly and also sticky. This I avoid by making the muffling-strip of a water-proof material, which does not absorb the water which is used in cleaning 50 the slate, and therefore always presents a neat, bright, and clean appearance, while such a muffling-strip is as durable as the ordinary strip.

What I claim as new, and desire to secure 60 by Letters Patent, is—

The combination, with a slate, of the attaching-frame extending around the edges of the slate and embracing the same, burrs or projections in said frame, and a muffling-strip over 65 the attaching frame, the edges of which lie between the slate and the attaching-frame and are penetrated by the burrs or projections of the latter, substantially as shown and described.

In testimony whereof I have hereunto set my 70 hand and seal in the presence of two subscribing witnesses.

PETER C. RITCHIE. [L. S.]
